UNITED STATES PATENT OFFICE.

MEREDITH G. STANLEY, OF CINCINNATI, AND ERNEST WHITE, OF MILFORD, OHIO;
SAID WHITE ASSIGNOR TO SAID STANLEY.

DISTRESS SIGNAL.

Application filed March 24, 1921. Serial No. 455,237.

To all whom it may concern:

Be it known that we, MEREDITH G. STANLEY and ERNEST WHITE, citizens of the United States, and residing at Cincinnati, in the county of Hamilton, State of Ohio, and Milford, in the county of Clermont and State of Ohio, respectively, have invented a new and useful Improvement in Distress Signals, of which the following specification is a full disclosure.

This invention relates to alarm devices, and is particularly adapted for use as a means for inspiring fear, and of stimulating flight, among bandits, sneak-thieves, cracksmen or other persons of malevolent intent.

In the use of this device the intention is to frighten the offenders, rather than to cause blood-shed or loss of life to either or both parties, which frequently results from an attempted use of fire-arms by those attacked.

It is well known that among those addicted to larceny, that the object is not to murder or to cripple, and it is only due to the resistance of their victims and to resulting fear of apprehension by the authorities that they turn to the use of fire-arms.

An object of our invention is therefore, to lessen the possibility of accident or death to those who are attacked, by providing for them, protection in the form of an alarm, or distress signal, of compact form, and of a size to be conveniently carried in the hand, which can be mechanically or chemically operated to cause the discharge of a number of blank cartridges, placed therewithin. The nature of this signal and the manner of its use precludes the probability of a dangerous attack by the robber, for he is immediately aware that there is no attempt on the part of his victim to injure him or to resist him.

Other objects and certain advantages will appear in the description of the drawing, forming a part of this specification, in which drawing:

Fig. 1 is an enlarged interior front face view of this improved distress signal, the cover plate having been removed.

Fig. 2 is a transverse section on line 2—2 of Fig. 1.

Fig. 3 is a rear face view, the cover plate having been removed.

Fig. 4 is a detail plan of the safety catch, the push-pin being shown in section.

Fig. 5 is a perspective view of one of the percussion and ignition caps.

The body of this device is of circular disk-like, magazine formation, is provided in its front face with a circular cavity 2, for housing the firing mechanism, with a rectangular, circumferential groove 3 in its rear face, for the reception and housing of the fuse, and with a series of circular cartridge-receiving openings 6 extending transversely through the body, a portion of each opening cutting the bottom 5 of the groove 3, to allow segmental portions of the blank-cartridges 7 placed within the said openings to project into the groove 3 and against the notched portion of the fuse 10 as hereinafter more fully described. The cartridge openings 6, as herein illustrated, are twelve in number and are designed to receive an equal number of blank cartridges, the same being placed, as shown, their firing ends engaging the rear of the body 1. Each cartridge is pierced to provide an opening 12, projecting within the groove 5, and in contact with a notch portion 11, of the fuse 10 (see Fig. 3). This piercing of the cartridge and notching of the fuse insures intimate contact of the powder grains, and resulting ignition and subsequent discharge of the blank cartridges when the fuse is lighted.

The fuse is placed within the groove, as shown, with its notched portions 11 consecutively engaged against the respective openings 12, of the series of blank cartridges. The free end of the fuse is then passed through an opening 15 to the forward face of the device, and thence across the cavity 2 and over and against the outer ends of the firing anvils 16, projecting outwardly from the bottom of the cavity 2. These anvils 16 have the form of rectangular posts, have screw threaded shanks 17, engaged with corresponding threaded openings in the base 1, and are placed in diametrical relation relative to a central pivot post 20, having screw threaded engagement with the base 1, and projecting from the bottom of the cavity 2. Over the anvils 16 are placed percussion caps 18, designed to be fired simultaneously by the diametrical arms of a rotating spring actuated hammer 19, the hub of which is traversed by the post 20, about which the hammer rotates. A torsion spring 21, for actuating the hammer 19, has one of its terminals connected with the post 20, and its

opposite terminal connected with the hub of the hammer 19 as shown. The terminal of the fuse 10 rests upon the top of one of the anvils and is fastened thereagainst by a 5 staple 10^a. The end of the fuse is frayed to thoroughly expose the powder grains therein to the flame of the fired cap, and that portion of the fuse lying over and against the other anvil is similarly frayed 10 for a like purpose. The flame from the caps will flash to the frayed portions of the fuse, igniting either one or both, after which the rapidly burning fuse will consecutively 15 ignite and discharge the blank cartridges. 15 A plug of asbestos 25 is inserted between the terminal of the fuse and that portion of the fuse which passes through the opening 15, to insure consecutive firing of the cartridges in one direction only.

20 A trigger 30 normally holds the hammer 19 in set position, with its spring 21 under tension. This trigger is pivoted at 31, and has a hook 32 at one extremity, for engagement over the trigger arm. A leaf spring 33 forces the hook into engaging position. 25 The opposite extremity 34, of the trigger, is engaged by the broad end 35, of a sliding pin 36, traversing a radial opening 37, of the body 1, the said pin projecting beyond the outer periphery of the body, and being provided with a finger disk 39. The pin 36 is notched at 40 and these notches are engaged by the edges of a slot 42, of a safety latch 41, slidably held against the outer face of 30 the body 1 by a screw 43, traversing said slot 42. The slot 42 is enlarged at 44, (see Fig. 4) and when the safety latch is thrown to the left, the edges of the slot are disengaged from the notches 40, to allow a depression of the pin 36, and subsequent release of the hammer 19.

The body 1 is provided at its peripheral corner with a notch 50, for the reception of a perforated spacing annulus 51. The perforations permit the escape of gases, and the free propagation of sound waves therethrough. Front and back covers, 55 and 56 respectively, form closures for the firing mechanism compartment and for the fuse and cartridge compartment. The front cover 55 is traversed by the outer end of the post 20, the end of which is flared to form a rivet head 20^a, to fasten said front cover against the annulus 51. The rear cover 56 is held against the body 1, by suitable screws 60, the heads of the blank cartridges resting against the inner face of said cover.

This alarm device is simple in operation and of convenient size to be carried and concealed in the hand. In use, the safety latch is thrown off, the hammer released by pressure upon the pin 36, to fire the caps 18, and ignite the quick fuse 10, immediately after which the device is thrown to the ground, 65 where the consecutive firing of the blank

cartridges takes place, giving the desired distress signal.

Having described our invention, we claim:

1. In a distress signal, a casing interiorly provided with a series of detonation chambers, a fuse channel within said casing in connection with each chamber, a trip hammer within said casing for exploding a cap to ignite a fuse within said fuse channel, and a means extending to the exterior of the 75 casing to release said trip hammer.

2. In a distress signal, a disk-like body traversed by a row of chambers, adapted to receive a plurality of blank cartridges, the casing of each cartridge having a perforation adjacent its closed end, a groove in said body surrounding said chambers, toward and into which project said perforations, a fuse having a plurality of inwardly facing notches, the apex of each notch contacting a projecting portion of a corresponding cartridge and perforation therein, and means for igniting said fuse to consecutively 80 explode said cartridges.

3. In a distress signal, a disk-like body 90 traversed by a row of chambers, adapted to receive and house a plurality of blank cartridges, the casing of each cartridge having a perforation adjacent its closed end, a groove in said body surrounding said chambers, toward and into which project said 95 perforations, a fuse having a plurality of inwardly facing notches, the apex of each notch contacting a projecting portion of a corresponding cartridge and perforation therein, and means for igniting said fuse to consecutively 100 explode said cartridges, said means comprising a double faced spring actuated hammer, adapted to fire percussion caps held by stationary anvils, against which 105 anvils the terminal portion of said fuse is held, a catch adapted to hold said hammer in set condition, and a sliding pin coacting to operate said catch to release said hammer.

4. In a distress signal, a disk-like body 110 providing a row of cartridge receiving chambers, adapted to house a plurality of blank cartridges, the casing of each cartridge being perforated adjacent its closed end; a groove in said body surrounding said chambers, toward and into which project said 115 perforations, a fuse having a plurality of inwardly facing notches, the apex of each notch contacting a projecting portion of a corresponding cartridge and perforation therein, means for igniting said fuse, and a perforated closure adjacent to and surrounding the muzzle ends of said cartridges, to permit free escape of gases, and free propagation of sound waves therethrough.

5. In a distress signal, a disk casing interiorly provided with an annular row of detonation chambers, each chamber adapted to receive a cartridge ignitable by a fuse, a 125 fuse channel connecting with said chamber.

bers, an oscillating, spring-tensioned trip hammer mounted centrally within the casting, for exploding a cap to ignite a fuse within said fuse channel, means for holding said hammer in a cocked position, and a trip rod accessible exteriorly of the casting for tripping said hammer-holding means, for releasing said hammer.

In witness whereof, we hereunto subscribe our names, as attested by the two subscribing witnesses.

MEREDITH G. STANLEY.
ERNEST WHITE.
